UNITED STATES PATENT OFFICE.

WILLIAM K. MEYER, OF BROOKLYN, NEW YORK, ASSIGNOR TO MEYER, BACHARACH AND FRIEDHEIM, OF NEW YORK, N. Y., A FIRM COMPOSED OF WILLIAM K. MEYER, ROBERT L. BACHARACH, AND ARTHUR FRIEDHEIM.

NECKTIE.

1,232,826.

Specification of Letters Patent. Patented July 10, 1917.

Application filed June 24, 1915. Serial No. 36,040.

To all whom it may concern:

Be it known that I, WILLIAM K. MEYER, a citizen of the United States, residing at Brooklyn, in the county of Kings and State 5 of New York, have invented certain new and useful Improvements in Neckties, of which the following is a specification.

The primary object of this invention is to preserve the shape and prevent the breaking down of the stitching and material of neckties of the four-in-hand or analogous type, due to the strain which these ties are subjected to in adjusting them on a collar, particularly turnover collars in which they frequently stick.

I am aware that others have sought to reinforce ties of this type by a fabric strip stitched to the inner face of the tie and provided with lines of reinforcing stitching 10 such, for example, as shown in U. S. patent to W. E. Webb, Jr., No. 1,079,382.

It will be observed, however, that in the Webb tie the reinforcing stitching; that is such stitching as passes entirely through 15 the body of the tie, is confined to the neck-band. The strip attached to the back of the tie extends throughout the neck-band portion, over the knot tying portion, and to the ends of the rear longitudinal seam of the 20 tie, or up to the points where the ends of the tie open, but the stitching which extends longitudinally over these portions of the tie extends through the reinforcing strip and the rear folds of the tie alone, and does not 25 pass entirely through the body of the tie.

In carrying out my invention, I secure to the rear face of the tie a reinforcing strip which, in the case shown, extends from the end of the main rear longitudinal seam of 30 the tie, or where the material of the smaller of the enlarged ends of the tie commences to open, to about the middle of the neck-band portion, and this strip is secured to the tie by lines of reinforcing stitching, 35 which extend throughout the length of the strip and pass entirely through the body of the tie throughout such length; that is to say, the stitches appear on the outer as well as the inner face of the tie.

By this arrangement the weakest portion 40 of the tie, or that portion which is subjected to the greatest strain and wear and tear is effectively reinforced and held in shape.

In order to more fully describe my said

invention, reference will be had to the accompanying drawings wherein,

Figure 1, is a view of the outer face of a four-in-hand tie embodying my invention;

Fig. 2, a view of the rear face or back of said tie, and

Fig. 3, an enlarged section on line 3^x—3^x Fig. 1.

The tie shown in the accompanying drawings, aside from the staying or reinforcing feature hereinafter described and which 45 constitutes the present invention, is a well known form of four-in-hand tie, consisting of two pieces of silk or other material joined by a bias seam 1, folded longitudinally, and stitched together by a seam 2 extending from 50 point 3 to point 4, from which points to the ends of the material the adjacent edges are free.

The material when thus folded forms a neck-band 5 which merges more or less gradually into two enlarged tying ends 6 and 7, 55 one of which ends, the end 6 in the present case, is smaller than the other.

Inclosed within the outer material of the tie is an inner lining 8 of any suitable ma- 60

terial.

In tying neckties of this character, it is that portion of the tie from the smaller of the enlarged tying ends to the neck-band, or what will be called the knot tying portion 65 of the smaller end of the tie, which is subjected to the greatest strain and wear and tear, because it is this portion which is pulled in adjusting the tie on the collar after the knot is tied or partially tied. This 70 strain has not only a tendency to pull the tie out of shape and cause it to become stringy, but it often results in breaking down bias seam 1, and in displacing the inner lining.

The object of the present invention therefore is to reinforce or stay this portion of the tie and cause it to hold its shape, and this I do in the present case by a strip of 75 flexible fabric 9, stitched to the rear face of the tie by rows of stitching 10, which extends entirely through not only the strip 9, but the outer face as well as the inner face of the outer material of the tie. This strip 80 extends from the point 3, or the end of the longitudinal seam 2, at the small end of the tie, to a point at or near the middle of the neck-band, the said strip being slightly nar-

rower than the neck-band of the tie, and the stitching 10 extending longitudinally of said strip adjacent its longitudinal edges, and then transversely thereof to form two 5 points 11 and 12.

The stitching 10 not only passes through the inner and outer faces of the main material of the tie and the strip 9, but it extends also through the inner lining 8. By 10 such an arrangement, the weakest portion of the tie, or that which is subjected to the greatest strain and distortion, is thoroughly stayed and held in shape.

The strip 9, in addition to performing the 15 function above described, may serve also as a tag or label on which to place a name or trade-mark.

The foregoing is a description of one specific embodiment of my invention which is 20 susceptible to modification without depart-

ing from the spirit of the invention here claimed.

What I claim is:

A necktie having a neck-band which merges into expanded or enlarged tying 25 ends the knot forming portion of the tie being embraced between the neck-band and said enlarged ends, a reinforcing strip of fabric forming an inner facing for the tie, and extending from said neck-band to one 30 of said tying ends and over one of the knot forming portions of said tie, and lines of stitching extending through said reinforcing strip and through the outer face of the body of the tie and longitudinally of said 35 tie from the neck-band to one of the tying ends.

In testimony whereof I affix my signature.

WILLIAM K. MEYER.
